UNITED STATES PATENT OFFICE.

JOHN S. COWDERY, OF SANDUSKY, OHIO.

MACHINE FOR MANUFACTURING CRAYONS, CARPENTERS' CHALK, &c.

SPECIFICATION forming part of Letters Patent No. 437,752, dated October 7, 1890.

Application filed June 6, 1887. Renewed December 3, 1888. Serial No. 292,440. (No model.)

To all whom it may concern:

Be it known that I, JOHN S. COWDERY, a citizen of the United States, residing at Sandusky, county of Erie, and State of Ohio, have 5 invented certain new and useful Improvements in Machines for Manufacturing Crayons, Carpenters' Chalk, or other Like Articles; and I do hereby declare the following to be a description of the same and of the manner of 10 constructing and using the invention in such full, clear, concise, and exact terms as to enable any person skilled in the art to which it appertains to construct and use the same, reference being had to the accompanying drawings, forming a part of the specification, the 15 principle of the invention being herein explained and the best mode in which I have contemplated applying that principle, so as to distinguish it from other inventions.

20 My invention has for its object an improvement in some of the mechanical forms of the principle of invention set out in my application for patent on a machine for the manufacture of crayons filed November 22, 1884, Serial No. 148,635. It has particular reference 25 to an improved form of link or mechanism for connecting together the different mold-plates in my improved machine for crayon-making.

Referring to the drawings, Figure 1 is a 30 plan view of a series of mold-plates connected together by one form of my improved links, certain parts being broken away and the mold-plates in closed position. Fig. 2 is an elevation view of a series of links of the same form 35 as those shown in Fig. 1. Fig. 3 is a perspective view of one link of this form. Fig. 4 is a plan view of another form of securing the mold-plates together, certain parts being broken away and the mold-plates in closed position. Fig. 5 is a perspective view of the end 40 portion of a mold-plate of the form shown in Fig. 4. Fig. 6 is a plan view of a series of links and mold-plates, the latter being in closed position, the links representing another 45 form of the invention, certain parts being broken away. Fig. 7 is a perspective view of the form of links shown in Fig. 6. Fig. 8 is a plan view of the parts shown in Fig. 6, the mold-plates being in open position, certain 50 parts being broken away. Fig. 9 is a perspective view of still another form of link.

Fig. 10 is a plan view of a series of links similar to that shown in Fig. 9 and mold-plates connected therewith, the latter in closed position, certain portions being broken away. 55 Fig. 11 is a plan view showing the same parts as shown in Fig. 10, the mold-plates being open. Fig. 12 is a detail plan of one mold-plate frame with the mold-plates and links in closed position, the form of the link being the 60 same as that shown in Figs. 6, 7, and 8. Fig. 13 is a detail in vertical cross-section of one of the mold-plate frames, omitting certain of the connecting parts. Fig. 14 is a vertical elevation of a series of links and mold-plates 65 on the line xx of Fig. 8, the mold plates being in section and in open position. Fig. 15 is a vertical elevation similar to Fig. 14, taken on the dotted line xx of Fig. 6, the mold-plates being in closed position. 70

Referring to Fig. 1, A represents the mold-plates provided with the shoulders $a a'$ and the tenon b . The link B is provided with the tongue c on its one edge and with the opening c' opposite thereto, in which the tongue 75 of the next succeeding link is placed. The link is provided with the shoulders $d d'$, and in the vertical opening d^2 between said shoulders the tenon b of the respective mold-plate closely fits, the shoulders $a a'$ of the respective mold-plates having bearing against the shoulders $d d'$ of the different links. 80

In the form of mechanism shown in Figs. 4 and 5, connecting the respective links of the series, each mold-plate A is provided at each 85 end with the vertical shoulder e on one side of its longitudinal face and on the opposite side with the rectangularly-formed vertical hook e' , in the opening e^2 of which the shoulder of the next succeeding mold-plate fits. 90

In the form shown in Figs. 6, 7, and 8 each mold-plate is formed at each end portion with the two vertical shoulders $f f'$, while the link in this form is provided with three shoulders, two of which $g g'$ are respectively formed at 95 the upper and lower face portions of one edge, and the third g^2 is formed on the central face portion of the opposite edge. Between the two shoulders $g g'$ is the space g^3 , in which the shoulder g^2 of the next link of the series fits. 100 Between the two shoulders $f f'$ is the opening f^2 . When the mold-plates and links are in

closed operative position, as shown in Fig. 6, the inner side f^3 of the shoulder f of each mold-plate has rigid engagement with the shoulder g^2 of the corresponding link and with 5 the shoulders $g' g'$ of the next link of the series, while the inner side f^3 of the shoulder f' has engagement with the shoulders $g' g'$ of the corresponding links when the links and mold-plates are in open operative position, as represented in Fig. 8.

In Figs. 9, 10, and 11 the links are formed with the two vertical shoulders $h h'$ extending unbrokenly from the upper to the lower portions, while the mold-plates are the same 15 in form as the mold-plates represented in Figs. 6 and 8. Between the two shoulders $h h'$ is the opening h^2 . The shoulder f' of one mold-plate and the shoulder f of the next succeeding mold-plate of the series fit in this opening h^2 ; or, in other words, in the opening f^2 , formed between the two shoulders of each mold-plate in the form as shown in Figs. 10 and 11, fits the shoulder h of one link and the shoulder h' of the next succeeding link of the 25 series. When the mold-plates and links are in closed operative position, as shown in Fig. 10, the shoulder f' of one mold-plate engages with the shoulder h of its corresponding link, the shoulder f being free from engagement 30 with the shoulder h' of the link. When the links and mold-plates are in open operative position, as shown in Fig. 11, the shoulders $h h'$ of one link respectively have rigid engagement with shoulder f' of one mold-plate 35 and shoulder f of the next succeeding mold-plate of the series.

The particular advantage which I gain by lessening the size of the links and reducing the number of shoulders in said links over 40 the form of links set forth in my said application, Serial No. 148,635, is that when the mold-plates are in open position, as shown in Figs. 8 and 11, the shoulders of the mold-plates are in rigid engagement with the shoulders of their corresponding links, whereby 45 any shuffling or lateral displacement of the mold-plates (when in this open position) is prevented, and they are held rigidly apart from one another, thus allowing the crayons 50 formed in the mold-plates to be easily removed without danger of breakage to the crayons. By the form of links shown in Figs. 5, 7, and 9 I am enabled also to remove any one mold-plate or link of the series without 55 displacing the remaining links or mold-plates, and by the use of the form shown in Figs. 1, 2, and 3 I may easily remove any one link by displacing but three mold-plates of the series.

The maintenance of the respective mold-plates in rigid position when open is the 60 result of the described construction, which operates to allow the independent play of movement of the parts, said play being equal to and no more than the distance through which 65 a mold-plate is moved from its companion mold-plate in order to release the articles molded between the two, such described con-

struction resulting in the respective parts having an aggregate play of movement equal to and no more than the distance required to move one mold-plate to release its molded articles, multiplied by the number of mold-plates in the series.

The various forms of mechanical construction set forth in this application are all comprised under the generic principle of invention set forth in my said prior application, Serial No. 148,635, these mechanical forms illustrating some of the modifications of which the principle of invention of said prior application is susceptible. It will therefore be understood that said broad principle of invention, necessarily shown in the different mechanical forms set forth in this application, does not constitute a part of the latter, and that all claim upon said broad principle of invention is rested in said other application, Serial No. 148,635.

I claim—

1. In a machine for the manufacture of crayons, carpenters' chalk, or other like articles, the combination, with a series of mold-plates, of mold-plate-actuating hook mechanism, said parts being constructed substantially as set forth, whereby shuffling or lateral displacement of the mold-plates when in open position is prevented, substantially as set forth. 90
2. In a machine for the manufacture of crayons, carpenters' chalk, or other like articles, the combination, with a series of mold-plates, of mold-plate-actuating hook devices interlocking with the latter, said parts constructed substantially as set forth, and having a relative play of movement equal to and no more than the distance required to move one mold-plate from another sufficiently to release the articles molded between the two, substantially 95 as set forth. 100
3. In a machine for the manufacture of crayons, carpenters' chalk, or other like articles, the combination, with a series of mold-plates, of mold-plate-actuating hook devices engaging therewith, said parts constructed, substantially as set forth, with interlocking portions having a certain play of independent movement, said play equal to and no more than the distance which a mold-plate is moved from its companion mold-plate to release its molded articles, substantially as set forth. 110 115

4. In a machine for the manufacture of crayons, carpenters' chalk, or other like articles, the combination, with a series of mold-plates, of mold-plate-actuating hook devices engaging therewith, said parts constructed substantially as set forth and respectively having a certain independent play, said play in aggregate being equal to and no more than the aggregate of distance required to move one mold-plate to release its molded articles, multiplied by the number of mold-plates in the series, substantially as set forth. 120 125 130

5. In a machine for the manufacture of crayons, carpenters' chalk, or other like articles, the combination, with a series of mold-plates,

of a series of mold-plate-engaging links, said parts constructed substantially as set forth, whereby the mold-plates when in open position are respectively maintained against shuffling or lateral movement, substantially as set forth.

6. In a machine for the manufacture of crayons, carpenters' chalk, or other like articles, the combination, with a series of mold-plates, of a series of links which open and close said mold-plates, said links having shoulders with

which the mold-plates respectively have rigid engagement when in open position, substantially as set forth.

In testimony that I claim the foregoing to be my invention I have hereunto set my hand this 3d day of June, A. D. 1887.

JOHN S. COWDERY.
